Patented June 26, 1962

193,090

SINK LINER MAT

Maurice H. Kraines, 4078 Monteith Drive, Los Angeles, Calif., and Robert L. Unkrich, Long Beach, Calif.; said Unkrich assignor to said Kraines

Filed Dec. 26, 1961, Ser. No. 68,055

Term of patent 14 years

(Cl. D9—6)

FIGURE 2 is a rear elevational view of said mat; and

We claim:

The ornamental design for a sink liner mat, substantially as shown.
